Application March 10, 1932. Serial No. 597,968

32 Claims. (Cl. 218—0.5)

This invention relates to methods of and apparatus for inserting fasteners. An apparatus exemplifying the invention is herein illustrated as embodied in an eyeleting machine of the gang type by which a plurality of eyelets may be inserted and clenched simultaneously.

In certain kinds of work it is necessary to connect two or more plates or layers of sheet material with a plurality of fasteners, such as eyelets or rivets, and to arrange the fasteners otherwise than in a straight row or line. Typical examples of work in which these conditions are encountered are found in electrical apparatus, such as radio-receiving sets, and ignition apparatus for internal combustion engines. Specifically, in one well-known electrical distributor for internal combustion engines a plate of electrical insulating material is secured to a plate of metal with five clenched eyelets so grouped that not more than three of the necessary five fastener-inserting tools similarly grouped are accessible to a raceway unit having a plurality of tracks or channels lying side by side. Still, although simultaneous insertion and 25 clenching of all the eyelets is desirable for economical production of such devices, it has heretofore been necessary to use at least two fastener-inserting machines successively to insert the required number of eyelets into each unit 30 of the work.

In view of the conditions above set forth, an object of the present invention is to provide improved means for automatically supplying fasteners to all the fastener-inserting tools of a gang in which access of a raceway to one or more of the tools is obstructed by one or more of the other tools.

To this end, and in accordance with a feature of the invention, the illustrated machine is provided with two confronting raceway units arranged at opposite sides of a gang of fastener-inserting tools, one of the units having a plurality of fastener-supplying channels arranged to present fasteners to certain tools of the gang, and the other unit having one or more such channels arranged to present fasteners to the other tool or tools of the gang, and mechanism for operating the raceway units by moving their delivery ends toward and from each other.

Again, it may be, as exemplified in the machine herein illustrated, that even when the duty of supplying fasteners to a gang of inserting tools is shared by two confronting raceway units, the proximity of one or more inserting tools of one group to one or more tools of the other group

will create the problem of avoiding physical interference between the delivery ends of the raceway units. Accordingly, to solve this problem, the delivery ends of the illustrated raceways are complementally articulated to clear each other 60 so that both may occupy fastener-presenting relation to their respective inserting tools at the same time.

Another object of the invention is to provide improved methods and improved apparatus 65 whereby the force and motion commonly required to insert fasteners may be supplemented by an additional force and motion, if need be, to insure complete insertion or permanently tight setting of the fasteners.

To this end, and in accordance with another feature of the invention, the illustrated machine is provided with slow-motion mechanism arranged to insert the fasteners, and percussion mechanism arranged to strike a blow on an element of the slow-motion mechanism in the direction of its fastener-inserting motion and in timed relation to its cycle of operation. Thus, when, as in the illustrated machine, the sudden impact produced by the percussion mechanism occurs 80 concurrently with completion of the slow inserting motion, it takes effect at that stage when resistance to insertion of the fastener or fasteners is greatest. This timing of the two mechanisms not only insures complete insertion of the fasteners but also enables a relatively light machine 85 to do relatively heavy work. Moreover, when such a method is used to insert and clamp tubular fasteners with a roll-clench it avoids splitting the clenched ends of the fasteners, since ample time 90 is afforded by the slow-motion mechanism for the metal of the fasteners to flow and stretch while the roll-clench is in process of development. Then, if any further flowing or stretching of the metal occurs as a result of a sudden impact 95 executed by the percussion mechanism the magnitude of transformation so produced is too slight to cause splitting of the clenched portions.

Referring to the drawings,

Fig. 1 is a front elevation of a fastener-inserting machine embodying the present invention;

Fig. 2 is a right-side elevation thereof, the right-hand raceway being omitted to avoid concealing other elements of the machine;

Fig. 3 is a top plan view of the machine omitting the right-hand raceway and a portion of the hammer;

Fig. 4 is a right-side elevation, partly in section, including the fastener-inserting plunger, slow-motion mechanism for operating the plunger, and

105

110

- percussion mechanism for supplementing the slow-motion mechanism;
- 5 Fig. 5 is a front elevation of the slow-motion mechanism (see line V—V in Fig. 4) and means for retracting the percussion element and timing the operation thereof;
- 10 Fig. 6 is a top plan view including a gang of anvils and the delivery ends of the two cooperative raceway units in their respective fastener-presenting positions;
- 15 Fig. 7 is a front elevation including a portion of the left-hand raceway unit and the mechanism for operating that unit;
- 20 Figs. 8, 9 and 10 are front elevations of individual parts all included in the assembly in Fig. 7;
- 25 Fig. 11 is a front elevation of the parts included in Fig. 5 but shows the parts in different positions;
- 30 Fig. 12 is a top plan view of a specimen of work into which ganged fasteners may be inserted by the illustrated machine; and
- 35 Fig. 13 is an elevation, partly in section, illustrating, on a magnified scale, a pair of cooperative setting tools in the act of clenching a tubular fastener of the type included in Fig. 12.
- 40 The specimen of work illustrated in Figs. 12 and 13 presents typical examples of the problems to which this invention is directed. This specimen comprises a plate 15 of sheet steel, a plate 16 of hard, compressed fiber, and five eyelets 17 connecting them and arranged otherwise than in a straight row, the plate 16 having the property of electrical insulation and being intended to support an electrical contact point in the primary circuit of an ignition apparatus. In commercial production of these assemblages it is required that all five of the eyelets 17 be inserted and clenched simultaneously, but it is to be understood that the holes for receiving the eyelets are formed in a prior operation.
- 45 The illustrated machine is provided with a gang of five fastener-inserting tools 21, 22, 23, 24, and 25 and with a complementary gang of five stationary anvils or clenching tools 26, 27, 28, 29, and 30 each arranged to cooperate with one of the fastener-inserting tools as illustrated in Fig. 13. Considering that the disposition or relative arrangement of the tools of both gangs must coincide with that of the fastener-receiving holes in the work-pieces as exemplified in Fig. 12, it is apparent that one or more of the fastener-inserting tools obstruct access to one or more of the others in any direction crosswise of the gang, and that it is therefore beyond the bounds of possibility to supply fasteners to all the tools with one fastener-supplying unit. Nevertheless, it is possible to supply fasteners simultaneously to all five of these tools with two raceway units, provided the delivery ends of the raceway units are moved toward and from each other, and provided, further, that both raceway units are designed to supply fasteners only to those tools that are not obstructively related to each other. To illustrate these points a broken line x—x is drawn on Fig. 6 in which the delivery ends of two raceway units 18 and 19 are represented in their respective fastener-presenting positions. These portions of the raceway units are movable toward and from each other in directions at right-angles to a vertical plan parallel to the line x—x. As illustrated in Figs. 2 and 4, the fastener-inserting tools 21 and 22 are obstructively related to each other and so are the tools 24 and 25, but the problem due to such relation is overcome, according to the present invention, by supplying fasteners through 55 one raceway unit to one tool of each obstructively related pair and through the other raceway unit to the other tool of each such pair. Accordingly, the illustrated machine is provided with two confronting raceway units 18 and 19 arranged at opposite sides of the gang of fastener-inserting tools, the raceway unit 18 being provided with channels 31 and 35 arranged to supply fasteners to the tools 21 and 25 respectively, while the raceway unit 19 is provided with channels 32 and 34 of unequal lengths arranged to supply fasteners to the tools 22 and 24 respectively. The raceway unit 18 is also provided with a relatively short channel 33 arranged to supply fasteners to the tool 23. Thus, one raceway unit having channels of unequal lengths is adapted to supply fasteners to all the tools at one side of the vertical plane of line x—x while the other unit also having channels of unequal lengths is adapted to supply fasteners to all the tools at the opposite side of that plane.
- 60 Since all the fastener-inserting tools are arranged at a common level it is necessary to arrange the delivery ends of the raceway units at a common level. Consequently, to avoid interference between the delivery ends of the raceway units when some of the fastener-inserting tools of both groups are nearly, if not quite, in alignment, as in the illustrated example, the present invention provides a novel feature of construction of the raceway units which consists in complementally articulated formations of their delivery ends, whereby the raceway units are enabled to present fasteners simultaneously to all the tools. The articulated formations above mentioned are illustrated in Fig. 6 in which the delivery ends of both raceway units are in their fastener-presenting positions. As shown in this figure the articulated formations comprise a salient 36 projecting from the raceway unit 19 and a complementary recess 37 formed in the raceway unit 18.
- 65 The stationary anvils or clenching tools 26, 27, 28, 29, and 30 are arranged to support the work-pieces against the downward pressure of the eyelet-inserting tools. As shown in Figs. 1, 120 2 and 6 the anvils are affixed in a block 40, and the latter is mounted on a horn or supporting arm 41 to which it is secured by bolts 42. The horn is adjustably attached to the main frame 43 of the machine by clamping bolts 44, the main 125 frame being provided with a flat, vertical attaching face or bed 45 against which a corresponding face of the attaching end of the horn is seated. Vertically extending slots 46 (Fig. 1) formed in the frame 43 to receive the bolts 44 provide for vertical adjustment of the horn. An 130 adjusting screw 47 having threaded connection with an intermediate portion of the horn is arranged to bear on an underlying rigid portion of the base 48 of the frame and thus to sustain in 135 part the downward pressure of the fastener-inserting tools as well as to adjust the anvils to the desired level when the clamping bolts 44 are relaxed. To maintain the horn rigidly in its right-side-up position the main frame and the horn are provided respectively with a vertical groove 49 and a rib 50.
- 70 The fastener-inserting tools 21, 22, 23, 24, and 25 are affixed in a block 51 carried by a vertically movable plunger 52, an upwardly projecting stem 145 formed on the block being secured in a socket in the plunger by a bolt 53.
- 75 The plunger 52 is arranged to slide in stationary guides 54, 54 bolted to an overhanging portion of the frame 43, and is reciprocated vertically by 150

a crank or wrist-pin 55 to which it is connected by a link 56 (see Figs. 4, 5 and 11). This crank is carried by a cam 57 the purpose of which is hereinafter described. The cam is affixed to a 5 horizontal operating shaft 58 journaled in bearings 59 in the frame 43.

A pulley 60 loosely mounted on the rear end of the shaft 58 is intended to be driven continuously by a belt (not shown). A suitable starting and 10 stopping clutch indicated as a whole at 61 in Figs. 2 and 3 is provided to establish driving connection between the pulley 60 and the shaft 58. A rod 62 for controlling the clutch is arranged to be connected to a treadle (not shown). As 15 shown in Fig. 2, a compression spring 63 surrounds the rod 62 and exerts upward pressure against a collar 64 affixed to the rod, the lower end of the spring being seated on the base 48 through which the rod extends. The spring normally 20 maintains the clutch 61 in a disconnected condition, but when the rod is depressed by the treadle it causes the clutch to operate the shaft 58.

Fig. 13 illustrates one of the pairs of cooperative tools by which an eyelet is inserted and clenched in an article of work, the inserting tool 24 being shown in its lowest position and the lower end of an eyelet 17 being represented as having been rolled back and clenched against the anvil or clenching tool 29 without being 30 split. Each anvil or clenching tool is provided with an annular clenching surface and with an upwardly projecting pilot or centering portion 20 adapted to occupy the holes previously formed in the work-pieces to receive the fasteners. 35 Thus, when the work-pieces are placed on the anvils 29 they are not only supported thereby but their fastener-receiving holes are maintained in alignment with the fasteners about to be inserted.

40 In accordance with common practice, each fastener-inserting tool is provided with a central spindle 65 normally projected downwardly by a spring (not shown), the spindle being arranged to enter the barrel of an eyelet in the delivery end of a raceway and to detach the eyelet from the raceway in consequence of retracting the latter.

As shown in Fig. 1 the two oppositely arranged raceway units 18 and 19 are connected 50 to the frame 43 by horizontal supporting pivots 63. Their delivery ends are moved simultaneously toward and from each other with oscillatory motion about these pivots. Two separate trains of mechanism are provided for operating the 55 raceway units respectively, and while some of the parts in these two trains of mechanism are not exactly duplicates in shape they are nevertheless duplicates in operation and principle. Under these circumstances, it will suffice to describe 60 the details of the train of mechanism for operating the left-hand raceway unit 18.

A duplex cam (see Fig. 2) carried by the shaft 58 is provided with a groove 70 in its front face for operating the raceway unit 18 and with a 65 groove 71 in its rear face for operating the raceway unit 19. The mechanism for operating the raceway unit 18 includes a horizontal rock-shaft 72, while that for operating the raceway unit 19 includes a similar rock-shaft 73, these two 70 shafts being arranged at opposite sides of the main power shaft 58 and being journaled in bearings 74 in the frame 43.

The operating connections for the raceway unit 18 are shown in Figs. 7, 8, 9 and 10. An arm 75 loosely mounted on the rock-shaft 72 communi-

cates motion from the cam 70 to the rock-shaft through the medium of a member shown separately in Fig. 9. This member comprises a hub and two lugs projecting therefrom, one of the lugs being indicated at 76 and the other being 80 provided with a socket 77 to receive one end of a compression spring 78. The arm 75 is provided with a socket 79 to receive the other end of the compression spring, and with a lug 80 arranged to abut the lug 76. In operation the lug 76 is normally maintained against the lug 80 by the spring but permits the lug 80 to move away from the lug 76 when the fastener-presenting movement of the raceway unit is arrested by an adjustable stop hereinafter described. The member shown in Fig. 9 is provided with a set-screw 81 for securing it rigidly to the rock-shaft. A cam-roll 82 carried by the arm 75 operates with the cam-groove 70.

The rocking motions of the shaft 72 are communicated positively to the raceway unit 18 by connections comprising an arm 83, a connecting link 84, and the parts shown in Fig. 10, the arm 83 being loosely mounted on the rock-shaft and angularly adjustable with respect thereto 100 according to the requirements of variously located fastener-inserting tools and variously designed raceway units with which the machine may be equipped. As shown in Fig. 10, an arm 85 mounted on the shaft 72 is provided with a 105 split hub and with a bolt 86 by which the hub may be contracted to clamp the shaft tightly. A key 87 is also provided to insure rigid connection of the arm 85 and the rock-shaft. An adjustable operating connection between the arm 85 and the loosely mounted arm 83 is provided by a draw-bolt 88, a set-screw 89, and a lug 90 formed on the arm 83. The draw-bolt 88 extends loosely through the arm 85 and is threaded in the lug 90, while the set-screw 89 is threaded 110 in the arm 85 and abuts against the lug 90. Thus the draw-bolt and the set-screw are arranged to maintain the arm 83 rigidly in a definite angular relation to the rock-shaft 72 and to regulate this angular relation as may be 115 required by the particular raceway unit affected thereby or by the particular fastener-inserting tool or gang of fastener-inserting tools with which the corresponding raceway unit is intended to cooperate.

To insure accurate register of the delivery end 120 of the raceway unit with the fastener-inserting tool or tools, the frame of the machine is provided with a bolt 91 (Fig. 7) the head of which serves as a stop against which a boss 92 on the 125 raceway unit is arranged to abut. The bolt 91 is screwed into the machine frame and is provided with a check nut 93. In practice, the draw-bolt 88 and the set-screw 89 (Fig. 10) will be adjusted to insure a slight over-throw of the 130 arm 75 after the raceway unit is arrested by the stop 91, the parts being thus caused to assume the positions represented in Fig. 7. The cam 70 and the spring 78 are thus rendered effective to 135 eliminate all back-lash or loose play in the operating connections when the raceway unit is in its fastener-presenting position.

Each raceway unit is provided with a hopper 95 from which fasteners are fed into the fastener-supplying channel or channels. Any suitable or preferred means, such as a rotary brush (not shown) may be mounted in the lower part of each hopper to feed the fasteners therefrom. As shown in Fig. 1, each hopper is provided with a pulley 96 for operating such a brush. These 140 145

pulleys are driven by belts 97 that run over sheaves 98 and in pulley-grooves 99 in the driving member of the clutch 61.

The fastener-inserting tools 21, 22, 23, 24, and 25 receive a slow harmonic motion from the operating crank 55 (Fig. 4), the range of which is sufficient to insert the fasteners into articles of work and clench them against the stationary anvils 26, 27, 28, 29, and 30. In some cases, as when the fastener-receiving material is soft in the sense that it is capable of being compressed at the points where the fasteners are inserted, a harmonic motion or other slow motion may be sufficient to insure tight clenching of the fasteners. On the other hand, when the fastener-receiving material or materials are hard and not capable of being so compressed, it is virtually impossible to effect tight clenching of the fasteners with a slow motion whether harmonic or not. This is presumably due in part to springing of machine parts under heavy stress and in part to resilience, however slight, of the metal of which the fasteners are made. In any event, although the fasteners may be clenched tightly while the tools are applying their maximum clenching pressure, the tightness ceases in many cases when the clenching pressure is discontinued.

To insure complete insertion of fasteners in hard materials and permanently tight clenching of fasteners such as eyelets and tubular rivets, the present invention provides improvements in methods of and apparatus for inserting and clenching fasteners, a percussion mechanism being provided to supplement the crank mechanism illustrated in Fig. 4. In the illustrated machine these two mechanisms are so combined that the crank mechanism functions first in a well-known manner to insert and clench the fasteners, a slow motion being desirable to avoid crumpling the barrels and splitting their clenched ends, after which, but while the co-operative fastener-engaging tools are still acting with pressure against opposite ends of the fasteners, the above-mentioned percussion mechanism may be caused to strike a blow on an element of the slow-motion mechanism in the direction of its fastener-inserting motion to set the clenched fasteners with permanent tightness. To this end, the operating connection between the link 56 and the plunger 52 is designed to permit over-travel of the plunger in the direction of its fastener-inserting motion to an extent that will permit the percussion mechanism to have the desired effect without encountering any opposition from, or doing any damage to, the crank 55 or the link 56.

As shown in Figs. 1, 2, 3, and 4, a hammer 100 is arranged to strike a downward blow against the upper end of the fastener-inserting plunger 52. The hammer is mounted on a supporting pivot 101 about which it is adapted to swing. Operating motion is imparted to the hammer by a strong torsion spring 102, one end of which is connected to the hammer and the other end of which is connected to an anchoring collar 103. This collar is rotatively adjustable to regulate the applied force of the spring 102 and may be maintained in various positions of adjustment by a locking pin 104 that extends through a hole 70 in the frame structure and may be inserted into any one of a circular series of sockets 105 formed in the collar 103.

The cam 57 by which the crank 55 is carried is formed and arranged to retract the hammer 100 and to release it when the crank is at bottom

center as shown in Fig. 11. For this purpose a vertically movable cam-follower 106 is interposed between the cam and the hammer and is arranged to slide in a guiding boss 107 formed on the frame 43. The lifting portion of the cam 57 extends through approximately 180 degrees and is effective through that portion of the cycle during which the crank-pin 55 moves from bottom center to top center. The other portion of 180 degrees of the periphery of the cam is concentric as indicated at 108 in Figs. 5 and 11. This concentric portion maintains the hammer at its highest position while the crank 55 is descending to insert and clench the fasteners with a slow motion, but when the crank is at or near bottom center as represented in Fig. 11, the cam follower 106 is released by an abrupt step 109 in the cam (see Fig. 11), whereupon the hammer strikes a sudden clench-tightening blow on the plunger 25. Under these conditions, the inertia of the mass comprising the horn 41, the block 40 and the anvils rigidly supported thereby, becomes effective to insure permanent tightness of the clenched fasteners irrespective of how much the frame structure and other elements may have been sprung by the stresses developed by the slow operation of the crank 55.

To provide for a slight over-travel of the fastener-inserting tools under the influence of the hammer 100 without breaking or straining the parts of the crank mechanism, the link 56 and the plunger 25 are connected by a lost-motion connection illustrated in Figs. 4, 5 and 11. For this purpose the lower end of the link is formed with a slot 110 in which a rectangular bushing 110 or block 111 is arranged to slide. A horizontal pivot stud 112 rigidly mounted in the plunger 25 extends through the block 111. The lower end of the slot 110 is closed by a cross-piece or cap 113 affixed to the link 56 by bolts 114. A helical spring 115 under initial compression is seated in a socket in the member 113 and normally maintains the block 111 against the upper extremity of the slot 110 as illustrated in Figs. 4 and 5, but when the hammer strikes a blow on the plunger 25 it drives the plunger and the block 111 slightly below the lower limit of travel previously imparted thereto by the crank 55, the block 111 being thereby depressed relatively to the link 56 as shown in Fig. 11. When, subsequently, the plunger 25 is raised by the crank, and the hammer 100 is raised by the cam 57, the lost-motion connection is restored to its normal relation by the spring 115 to insure positive operation of the fastener-inserting tools by the crank 55 during the next subsequent cycle of operations.

When the percussion mechanism is used to supplement the crank mechanism, the cycle of operations is as follows. The parts stand initially in the positions represented in Figs. 1, 2, 4, 5, 6, and 7, the fastener-inserting tools being then at their highest level, and the eyelets at the delivery ends of the raceway units being in register with the fastener-inserting tools and the anvils. After tripping the operating clutch 61, the operator will release the controlling treadle immediately, to the end that the shaft 58 will be arrested at the completion of each cycle. As the gang of fastener-inserting tools descends, the spindles 65 thereof enter the barrels of the leading eyelets 65 in the raceway units, whereupon the raceway units are retracted far enough to clear the block 51 in which these tools are secured. Assuming that a plate 15 of metal and a plate 16 of compressed fiber have been placed on the anvils 150

as represented in Fig. 13, the eyelets will be carried nearly, if not quite, to them by the spindles 65. When the downward movement of the spindles is arrested by the pilots 20 of the anvils 5 the eyelets will be stripped from the spindles and inserted into the work-pieces 15 and 16 by the fastener-inserting tools. The range of motion imparted to the fastener-inserting tools by the crank 55 is sufficient to roll back and clench the lower ends of the eyelets as shown in Fig. 13, the inserting and clenching pressure being applied to the flanges at the upper ends of the eyelets. Up to this point in the cycle the hammer 100 10 is maintained at its highest level by the concentric portion 108 of the cam 57, but when the crank is about to pass its lower dead-center position the step 109 releases the hammer. The blow struck by the hammer occurs coincidentally with the completion of the slow fastener-inserting 15 motion by which the lower ends of the eyelet barrels are rolled back and clenched and by which the flanges at the upper ends of the eyelets are seated against the upper surface of the work-piece 15. Moreover, the blow is struck at the instant when the pressure developed by the crank 20 mechanism is of maximum degree. The forces thus derived from two sources are combined to insure complete insertion of the eyelets and to eliminate all space or looseness between the work-pieces 15 and 16. Moreover, the sudden impact 25 of the hammer 100 under these conditions imparts a permanent set to the clenched portions of the eyelets and embeds them slightly in the fiber piece 16, the rims of the anvils being preferably provided with sharp circular edges to provide backing for the edges of the clenched portions without projecting beyond the latter.

As the crank 55 progresses from the bottom center to top center it returns the fastener-inserting tools to their initial level (Fig. 1), the cam 57 meanwhile raising the hammer 100. When the fastener-inserting tools have nearly reached their highest level the delivery ends of the raceway units are moved toward each other to place another gang of eyelets in register with the spindles 65, and when all the parts have returned to their initial positions the shaft 58 is arrested automatically by stopping elements combined with the clutch mechanism.

If it be desired to use the slow-motion fastener-inserting mechanism without using the percussion mechanism, as when inserting fasteners in relatively soft or compressible fastener-receiving material, the hammer 100 may be maintained 50 out of operation by locking the cam follower 106 in its raised position. For this purpose, the illustrated machine is provided with a manually controllable locking member 116 (Figs. 2, 3 and 5) arranged to be thrown into a notch 117 formed 55 in the follower 106. The locking member is supported on the upper surface of the guiding boss 107 to which it is connected by a pivot stud 119. A finger-piece or operating handle 118 is formed on the locking member 116. As shown in Fig. 3 60 the locking member is retracted from the notch 117. An angular movement of 90 degrees or less about the pivot stud 119 is sufficient to place the effective portion of the locking member in the notch 117. The notch is in register with the locking member only when the follower 106 is at 65 the upper limit of its travel as illustrated in Fig. 5.

Having thus described my invention, what I claim as new and desire to secure by Letters Patent of the United States is:

75 1. A fastener-inserting machine comprising a

gang of fastener-inserting tools, operating mechanism by which fastener-inserting movement is imparted thereto, two confronting raceway units arranged at opposite sides of said gang of tools, one of said raceway units having a plurality of fastener-supplying channels arranged to present fasteners to certain of said tools and the other having one or more such channels arranged to present fasteners to the other tool or tools of the gang, and mechanism for operating said raceway units by moving their delivery ends toward and from each other. 80

2. A fastener-inserting machine comprising a gang of fastener-inserting tools arranged otherwise than in a straight row, operating mechanism by which fastening-inserting movement is imparted thereto, two confronting fastener-supplying units arranged at opposite sides of said gang of tools, one of said units having means arranged to present a crooked row of fasteners to correspondingly arranged tools of said gang, and the other one of said units having means arranged to present fasteners to one or more other tools of said gang, and mechanism for operating said units simultaneously. 85

3. A fastener-inserting machine comprising a gang of fastener-inserting tools arranged otherwise than in a straight row, operating mechanism by which fastener-inserting movement is imparted thereto, two confronting raceway units 105 arranged at opposite sides of said gang of tools, one of said units having a plurality of fastener-supplying channels of unequal lengths arranged to present fasteners to certain of said tools, and the other one of said units having one or 110 more channels arranged to present fasteners to one or more other tools of the gang, and mechanism for operating said raceway units simultaneously.

4. A fastener-inserting machine comprising a gang of fastener-inserting tools one or more of which obstruct presentation of fasteners to one or more others from one side of the gang, operating mechanism by which fastener-inserting movement is imparted to said gang of tools, two 120 confronting raceway units arranged at opposite sides of said gang of tools, one of said raceway units having a plurality of fastener-supplying channels arranged to present fasteners to tools accessible from one side of said gang and the other having one or more fastener-supplying channels arranged to present fasteners to the other tool or tools of the gang, and mechanism for operating said raceway units by moving their delivery ends toward and from each other. 125

5. A fastener-inserting machine comprising a gang of fastener-inserting tools a plurality of which are arranged at one side of a line and one or more of which are arranged at the opposite side of said line, operating mechanism by which fastener-inserting movement is imparted to said gang of tools, two confronting raceway units arranged at opposite sides of said line, one of said units having a plurality of fastener-supplying channels arranged to present 135 fasteners to the tools at one side of said line and the other having one or more channels arranged to present fasteners to the tool or tools at the opposite side of said line, and mechanism for operating said raceway units by moving their delivery ends toward and from each other.

6. A fastener-inserting machine comprising a gang of closely spaced fastener-inserting tools, operating mechanism by which fastener-inserting movement is imparted thereto, two confronting 140

150

- raceway units oppositely arranged to present fasteners to said tools at a common level, one of said units having a plurality of fastener-supplying channels and the other having one or more 5 such channels the delivery ends of which are offset laterally from alignment with those of the first-mentioned channels, and the delivery ends of said units being complementally articulated to clear each other, and mechanism for operating 10 said raceway units by moving their delivery ends toward and from each other.
7. A fastener-inserting machine comprising a gang of fastener-inserting tools, an operating shaft, two individually movable raceways arranged 15 at opposite sides of the axis of said shaft, means carried by said shaft for operating said raceways to present fasteners to said tools, and means carried by said shaft for operating said gang of tools to insert the fasteners.
- 20 8. A fastener-inserting machine comprising two individually movable raceways arranged in opposed relation to each other, a gang of fastener-inserting tools movable between the delivery ends of said raceways, mechanism arranged to operate 25 said raceways to present fasteners to said tools by moving their delivery ends toward and from each other, and mechanism arranged to operate said tools to insert the fasteners.
9. A fastener-inserting machine comprising 30 two pendent oscillatory raceways the delivery ends of which are underslung and extend toward each other at a common level, a plunger arranged between said raceways and provided with a gang of fastener-inserting tools, an operating 35 shaft the axis of which lies between said raceways, means carried by said shaft for operating said raceways to present fasteners to said tools, and means carried by said shaft for operating said plunger to insert the fasteners.
- 40 10. A fastener-inserting machine comprising fastener-inserting means, a movable raceway arranged to present fasteners to said means, an abutment arranged to arrest said raceway in its fastener-presenting position, and power-driven 45 mechanism arranged to move the delivery end of said raceway to and from the position determined by said abutment, said mechanism including a resilient connection arranged to yield when the raceway is arrested by said abutment.
- 50 11. A fastener-inserting machine comprising fastener-inserting means, a movable raceway arranged to present fasteners to said means, a power-operated rockshaft for operating said raceway, an arm loosely arranged on said rockshaft and operatively connected to said raceway, a member rigidly secured to said rockshaft adjacent to said arm, and two cooperative adjusting screws by which said arm and said member are positively connected and by which the angular 55 relation of the arm and said rockshaft may be regulated.
12. A fastener-inserting machine comprising work-supporting means, slow-motion mechanism arranged to insert a fastener into work sustained 60 by said work-supporting means, and percussion mechanism arranged to strike a blow on an element of said slow-motion mechanism in the direction of its fastener-inserting motion and in timed relation to its cycle of operation.
- 70 13. A fastener-inserting machine comprising working-supporting means, a fastener-inserting member movable toward and from said means, a crank arranged to operate said member, and percussion mechanism controlled to operate in timed 75 relation to said crank and arranged to strike a blow against said fastener-inserting member in the direction of its fastener-inserting motion when said crank is passing a dead-center position.
14. A fastener-inserting machine comprising work-supporting means, a plunger movable toward and from said means, a fastener-inserting tool carried by said plunger, an operating shaft, operating means carried by said shaft by which slow fastener-inserting motion is imparted to said plunger, a spring-stressed hammer arranged to strike a blow against said plunger in the direction of its fastener-inserting motion, and means carried by said shaft to retract and release said hammer in timed relation to said slow-motion operating means. 80
15. A fastener-inserting machine comprising a plunger, a fastener-inserting tool carried thereby, work-supporting means, operating mechanism including a crank by which harmonic fastener-inserting motion is imparted to said plunger, said operating mechanism and said plunger having a lost-motion connection, and percussion mechanism arranged to strike a blow against said plunger in the direction of its fastener-inserting motion in timed relation to the operation of said crank. 85
16. A fastener-inserting machine comprising a plunger, a fastener-inserting tool carried thereby, work-supporting means, operating mechanism by which a slow fastener-inserting motion is imparted to said plunger, said operating mechanism and said plunger having a lost-motion connection, and percussion mechanism arranged to strike a blow against said plunger in the direction of its fastener-inserting motion in timed relation to the operation of said slow-motion operating mechanism. 90
17. A fastener-inserting machine comprising cooperative setting tools arranged to operate against opposite ends of a fastener, mechanism for relatively moving said tools with a slow motion to upset and clench a fastener, and percussion mechanism arranged to strike a clench-tightening blow against one of said tools in timed relation to the clenching movement of the mechanism first specified. 105
18. A fastener-inserting machine comprising cooperative setting tools arranged to operate against opposite ends of a fastener, mechanism for moving one of said tools toward the other with an approximately harmonic motion to upset and clench a fastener, and percussion mechanism arranged to strike a clench-tightening blow against one of said tools in timed relation to the clenching movement of the mechanism first specified. 110
19. A fastener-inserting machine comprising cooperative setting tools arranged to operate against opposite ends of a fastener, a crank-motion arranged to move one of said tools toward the other to upset and clench a fastener, and percussion mechanism arranged to strike a clench-tightening blow against one of said tools in timed relation to the clenching motion of said 115 crank-motion. 135
20. A fastener-inserting machine comprising cooperative setting tools arranged to operate against opposite ends of a fastener, a crank and means operated thereby for moving one of said 140 tools toward the other to upset and clench a fastener, and percussion mechanism arranged to strike a clench-tightening blow against one of said tools when said crank is adjacent to its "dead-center" clenching position. 145

21. A fastener-inserting machine comprising a fastener-inserting tool, mechanism for operating said tool with a slow fastener-inserting motion, a striker arranged to strike a blow against said tool in the direction of its inserting motion, a spring arranged to operate said striker, and means under control of said operating mechanism by which said striker is initially restrained and thereafter tripped to supplement said slow fastener-inserting motion with a sudden impact. 5
22. A fastener-inserting machine comprising cooperative setting tools arranged to operate against opposite ends of a fastener, mechanism arranged to operate one of said tools with a slow motion to upset and clench a fastener, a striker arranged to strike a blow against one of said tools in the direction of the other one of the tools, a spring arranged to operate said striker, and means under control of said mechanism for initially restraining and thereafter tripping said striker to supplement the clenching effect produced by said slow motion. 10
23. A fastener-inserting machine comprising cooperative setting tools arranged to operate against opposite ends of a fastener, mechanism arranged to operate one of said tools with a slow motion to upset and clench a fastener, the operating connection between said one of said tools and said operating mechanism being formed to permit that one of the tools to run ahead of said mechanism, and percussion mechanism arranged to drive said one of the tools ahead of said operating mechanism with a sudden impact to supplement the clenching effect produced by said operating mechanism. 15
24. A fastener-inserting machine comprising a plunger, one or more fastener-inserting tools carried thereby, means arranged to cooperate with said one or more tools to clench the fasteners, operating mechanism including a crank by which harmonic fastener-inserting motion is imparted to said plunger, said operating mechanism and said plunger having a lost-motion connection, and percussion mechanism arranged 20 to strike a clench-tightening blow against said plunger in timed relation to the operation of said crank.
25. A fastener-inserting machine comprising work-supporting means, a fastener-inserting member movable toward and from said means, a spring-stressed hammer arranged to operate said member, and rotary driven means arranged to retract said hammer and operate said member with a slow motion. 25
26. A fastener-inserting machine comprising work-supporting means, a fastener-inserting member movable toward and from said means, a spring-stressed hammer arranged to operate said member, rotary driven means arranged to retract said hammer and operate said member with a slow motion, and manually movable controlling means by which said hammer may be restrained from operating without preventing operation of said slow-motion means. 30
27. A fastener-inserting machine comprising a frame and a detachable work-supporting horn
- having cooperative flat vertical attaching faces provided one with a vertical groove and the other with a complementary rib to maintain the horn positively in a predetermined upright position, means arranged to clamp said horn against said attaching face of the frame, a fastener-clenching anvil mounted at the outer end of said horn, fastener-inserting mechanism arranged to cooperate with said anvil, said frame also having a rigid portion underlying an intermediate portion of said horn, and adjustable means engaging said rigid portion of the frame and said intermediate portion of the horn to brace the latter against the stresses imposed by said fastener-inserting mechanism. 35
28. That improvement in methods of securing fasteners which consists in inserting into a work-piece a ductile metal fastener having a flange at one end and a tubular formation at the opposite end, rolling back said tubular formation to form a roll-clench at a speed sufficiently slow to avoid splitting the metal thereof, and thereafter tightening the fastener by striking a blow against one end thereof while the other end is seated against an anvil. 40
29. That improvement in methods of securing fasteners which consists in inserting into a work-piece a ductile metal fastener having a flange at one end and a tubular formation at the opposite end, rolling back said tubular formation to form a roll-clench at a speed sufficiently slow to avoid splitting the metal thereof, and thereafter tightening the fastener by striking a blow against the flanged end thereof while the clenched end is seated against the anvil by which the roll-clench was developed. 45
30. That improvement in methods of inserting fasteners which consists in inserting a fastener having a head or flange into a work-piece with one continuous slow motion until the head or flange is seated against the work-piece, and striking a blow against the fastener in the direction of its inserting motion coincidentally with the completion of the slow inserting motion. 50
31. That improvement in methods of inserting fasteners which consists in inserting a fastener having a head or flange into a work-piece with one harmonic motion of a length to seat the head or flange against the work-piece, and striking a blow against the fastener in the direction of its inserting motion coincidentally with the completion of the harmonic inserting motion. 55
32. That improvement in methods of securing fasteners which consists in inserting into a work-piece and against an upsetting anvil contiguous thereto a ductile metal fastener having a tubular formation at its leading end and a flange or head at its trailing end with one harmonic motion of a length to upset and clench the leading end, and striking a clench-tightening blow against one end of the clenched fastener coincidentally with the completion of the harmonic inserting motion. 60
